(57) **CLAIM**

The ornamental design for a visual learning product, as shown and described.

DESCRIPTION

FIG. 1 is a top plan view of a first embodiment of a visual learning product showing my new design;

FIG. 2 is a top plan view of a second embodiment of a visual learning product showing my new design; and,

FIG. 3 is a top plan view of a third embodiment of a visual learning product showing my new design.

The visual learning product is a flat surface. The front view, the rear view, the left side view, the right side view, and the bottom view form no part of the claimed design.

The dot-dash broken lines and dot-dot-dash broken lines depict the bounds of the claimed design and form no part of the claimed design. The evenly spaced broken lines are directed to environment and form no part of the claimed design.

1 Claim, 3 Drawing SheetsFIG. 1

FIG. 2

FIG. 3
